UNITED STATES PATENT OFFICE

130,040

DESIGN FOR A FLYING BOAT

Isaac M. Laddon, San Diego, Calif., assignor to
Consolidated Aircraft Corporation, a corpora-
tion of Delaware

Application January 10, 1941, Serial No. 97,953

Term of patent 14 years

To all whom it may concern:

Be it known that I, Isaac M. Laddon, a citizen
of the United States, residing in the city of San
Diego, in the county of San Diego and State of
California, have invented a new, original and or-
namental Design for a Flying Boat, of which the
following is a specification, reference being had
to the accompanying drawings, forming part
thereof:

Fig. 1 of the drawings is a plan view of a fly-
ing boat embodying the new design;

Fig. 2 is a front elevational view of the same;

Fig. 3 is a side elevational view; and

Fig. 4 is a perspective view thereof.

I claim:

The ornamental design for a flying boat, sub-
stantially as shown.

ISAAC M. LADDON.
